CHORD PLAYING ATTACHMENT FOR
STRINGED INSTRUMENTS

Ernest L. La Rose, New Britain, Conn.

Application February 18, 1949, Serial No. 77,161

4 Claims. (Cl. 84—317)

1

This invention relates to stringed musical instruments, and more particularly to an attachment for use on a guitar or similar instrument which enables chords to be played in a very simple and easy manner.

A main object of the invention is to provide a novel and improved chord playing attachment for stringed instruments such as guitars, said attachment being very simple in construction, easy to install, and not requiring any changes or alterations in the construction of the instrument on which it is mounted.

A further object of the invention is to provide an improved key-operated mechanism adapted to be mounted on the finger board of a guitar or other stringed instrument, said mechanism permitting the musician to play chords by simple and easy manipulations of the keys thereof, being inexpensive to manufacture and positive in action.

Further objects and advantages of the invention will become apparent from the following description and claims, and from the accompanying drawings, wherein:

Figure 1 is a top plan view of a chord playing attachment constructed in accordance with the present invention, shown mounted on the finger board of a guitar.

Figure 2 is a bottom plan view of the chord playing attachment of Figure 1.

Figure 3 is a front end elevational view of the attachment of Figure 1, the neck of the guitar being shown in dotted view.

Figure 4 is a rear end elevational view of the chord playing attachment of Figure 1.

Figure 5 is a side elevational view of the chord playing attachment of Figure 1.

Figure 6 is a longitudinal cross-sectional view taken on line 6—6 of Figure 2.

Figure 7 is a cross-sectional view taken on line 7—7 of Figure 6.

Figure 8 is a detail cross-sectional view taken on line 8—8 of Figure 7.

Figure 9 is a detail cross-sectional view taken on line 9—9 of Figure 7.

Figure 10 is a fragmentary detail cross-sectional view taken on line 10—10 of Figure 2.

Figures 11 to 14 are front elevational views of respective string-engaging members employed in the chord-playing attachment of Figure 1.

Referring to the drawings, the chord-playing attachment is designated generally at 10. Said attachment comprises a generally rectangular elongated housing 11 having longitudinal side walls 12 and 13 and respective end walls 14 and 15, defining a generally rectangular cavity within the housing. The width of the housing 11 is substantially the same as the width of the neck of a guitar, such as the guitar neck 16 illustrated in Figure 1.

Hinged at 17, 17 to the sides of housing 11 ad-

2

jacent the forward end wall 15 are the clamp arms 18, 18. Extending through the clamp arms 18, 18 and through the end wall 15 transversely of the housing 11 is a bolt 19 provided outwardly adjacent one of the clamp arms, with a wing nut 20. As shown in Figure 3, the clamp arms 18 are curved downwardly and inwardly to conform with the contour of the side portions of the neck of the guitar. The inside surfaces of the clamp arms 18 are provided with soft pads 21, 21, of felt or the like, engageable with the neck of the guitar in the manner shown in Figure 3, so that when wing nut 20 is tightened, the neck of the guitar will not be marred by the clamp arms 18, 18.

Secured to the sides of housing 11 adjacent the rear end wall 14 is a clamping strap 22 of leather or other suitable flexible material, engageable around the neck of the guitar in the manner shown in Figure 4. As shown in Figure 4, one end of strap 22 is connected to a pin 23 secured between lugs 23', 23' depending from a rear corner portion of housing 11. The other end of the strap 22 is secured to the head of an inverted T-bolt 24 whose shank extends upwardly through an apertured bracket 25 secured to the other rear corner portion of the housing and projecting laterally therefrom. Threaded on the shank of bolt 24 is a wing nut 26. When the strap 22 is engaged around the neck of the guitar in the manner shown in Figure 4, said strap may be tightened, so as to clampingly engage the guitar neck, by tightening the wing nut 26.

Pivotedly secured at its intermediate portion to the rear end wall 14 is a transverse vertical plate member 28 having an arcuately curved bottom edge 29 which extends below the bottom plane of housing 11. The arcuate edge 29 is formed with spaced notches 30 through which the guitar strings pass when the attachment is mounted on a guitar. The pivot screw, shown at 27, secures plate member 28 to end wall 14 but allows the housing 11 to be adjusted angularly around the axis of the screw.

Secured to the bottom marginal surface of front end wall 15, is a bracket 31 having depending longitudinal side flanges 32, 32 engageable with the top surface of the guitar neck to provide a front bearing for the housing 11. The flanges 32, 32 are spaced so as to be located inwardly of and parallel to the end strings of the guitar without touching the strings, as shown in Figure 3.

When the housing 11 is clamped on the neck of a guitar by the clamp arms 18, 18 and the strap member 22 in the manner shown in Figures 3 and 4, the rear plate member 28 and the front longitudinal flanges 32, 32 bear on the top surface of the guitar neck and support the housing in inverted upwardly spaced relation to said top surface and also in upwardly spaced rela-

tion to the guitar strings. The guitar strings are designated at 33 to 38 respectively.

Designated at 39, 40 and 41 are respective longitudinally spaced rectangular plate members contained within the housing and vertically movable therein. Each plate member is formed with a pair of counter-bored apertures 51. Extending axially through the openings 51 and secured to the top wall of housing 11 are respective headed bolts 52. Encircling the bolts 52 and bearing between the bolt heads and the counter-bores are coiled springs 53, biasing the plate members 39, 40 and 41 against the top wall of the housing. Plate member 39 has pivotally secured to its opposite ends the respective transverse vertical plate elements 54 and 55. Plate member 40 has pivotally secured to its opposite ends the respective transverse vertical elements 56 and 57. Plate member 41 has pivotally secured to its opposite ends the respective transverse vertical plate elements 58 and 59. Each of the plate elements 54 to 59 is formed with a pair of spaced depending lugs, as shown at 60, 61, 62, 63, 64, 65, 66, 67, 68, 69, 70 and 71 in Figure 2. The transverse spacing of these lugs varies with each of the plate elements. However, it may be seen from Figure 2 that the lugs 62, 66 and 70 are longitudinally aligned and overlie the string 38 of the guitar; the lugs 60 and 68 are longitudinally aligned and overlie the next string 37; the lug 64 overlies the next string 36; the lugs 63, 67 and 71 are longitudinally aligned and overlie the next string 35; the lugs 61 and 69 are longitudinally aligned and overlie the next string 34; the lug 65 overlies the last string 33.

The top surface of plate member 41 is formed with a transverse groove 49. Designated at 42 is a lever extending transversely through the housing and pivoted at one end to a longitudinal hinge pin 43 carried in brackets 44 and 45 secured to the side wall 13 of the housing. Lever 42 extends through vertical slots 46 and 47 formed in the side walls of the housing. At its free end lever 42 is provided with a finger tab 48. The plate member 41 may be depressed with respect to the top wall 50 of the housing 11 by depressing the finger tab 48. This engages lug 70 with string 38, lug 68 with string 37, lug 71 with string 35, and lug 69 with string 34.

The top surface of plate member 40 is formed with a transverse groove 72 which receives a second transverse lever 73 pivoted at one end to pin 43 and provided at its free end with a finger tab 74. Lever 73 passes through vertical slots 75 and 76 formed in the side walls of housing 11. When lever 73 is depressed, plate member 40 is moved downwardly, engaging lug 66 with string 38, lug 67 with string 35, lug 64 with string 36, and lug 65 with the string 33.

The top surface of plate member 39 is formed with a transverse groove 77 which receives a third transverse lever 78 pivoted at one end to a pin 79 carried by the side wall 13 of housing 11. The free end of lever 78 is provided with a finger tab 80. Lever 78 passes through vertical slots 81 and 82 formed in the side walls of housing 11. When lever 78 is depressed, plate member 39 is moved downwardly, engaging lug 62 with string 38, lug 60 with string 37, lug 63 with string 35, and lug 61 with string 34.

Designated at 83 is a transverse lever pivoted at 84 to rear end wall 14 adjacent the side wall 12. Lever 83 extends through a vertical slot 85 formed in side wall 13 and the free end of lever is provided with a finger tab 86. Pivoted to the inter-

mediate portion of lever 83 and extending parallel to and adjacent the plate element 54 is a plate element 87. Plate element 87 is formed with depending lugs 88 and 89. Lug 89 is of the same size as the lugs heretofore described and overlies the string 33. Lug 88 is twice as long as lug 89 and overlies strings 35 and 36. Lever 83 is biased upwardly against top wall 50 by a spring 90 acting between the bottom edge of said lever and a lug 91 secured to rear end wall 14 and underlying said lever. When finger tab 86 is depressed, plate element 87 is moved downwardly, causing lug 89 to engage string 33 and lug 88 to simultaneously engage strings 35 and 36.

Designated at 92 is a longitudinally extending lever pivoted at 93 to the inner side of side wall 13. Lever 92 is formed at its free end with a laterally projecting arm 94 which extends through a vertical slot 95 formed in side wall 13. The end of arm 94 is provided with a finger tab 96. Lever 92 is biased upwardly by a spring 97, as shown in Figure 10, which acts between the bottom edge of said lever and an inwardly projecting lug 98, secured to side wall 13 in underlying relation to the lever. Pivoted at 99 to lever 92 is a Z-shaped vertical plate member 100. The body portion of plate member 100 is longitudinally aligned with the space intermediate strings 33 and 34, as shown in Figure 2. At its forward end plate member 100 carries the transverse lug 101 which overlies the string 33. At its rear end plate member 100 carries the transverse lug 102 which overlies the string 34. When finger tab 96 is depressed, plate member 100 is moved downwardly, causing lug 101 to engage string 33 and lug 102 to engage string 34.

It will be seen from Figure 2 that plate elements 54 and 57 carry a first group of depending lugs comprising lugs 68, 83, 61 and 89. Plate elements 55 and 56 carry a second group of lugs comprising lugs 62, 64, 63 and 65. Included in this second group is the lug 102 carried by plate member 100. A third group of lugs comprises lugs 66, 68, 67 and 69 and 101. A fourth group comprises the lugs 70 and 71. The respective groups of lugs above described are spaced longitudinally at distances corresponding to the distances between successive frets on the neck of the guitar.

It will be apparent that by depressing different finger tabs the strings of the guitar will be engaged in different ways, whereby different chords may be produced when the strings are struck. For example, assume that the strings 33 to 38 are tuned to provide the respective tones G, B, D, G, B, D. When the strings are struck this produces a first desired chord, namely G chord, on open string actuation. When finger tab 86 is depressed, strings 33, 35 and 36 will be stopped at the rearmost fret. When the strings are struck, string 33 will vibrate to provide the tone of G sharp, string 35 will provide the tone of D sharp, and string 36 will provide the tone G sharp.

When finger tab 80 is depressed, strings 34 and 37 will be stopped at the rearmost fret and strings 35 and 38 will be stopped at the second fret. When the strings are struck, string 34 will provide the tone C and string 37 will provide the tone C. String 35 will provide the tone E and string 38 will also provide the tone E. In combination with the tones of the remaining strings, a second desired chord is produced. In a similar manner, various other desired chords may be produced by depressing the other finger tabs prior to striking the strings. Tabs 86 and 96 are used to make

available the half-tones necessary to play a melody in which sharps and flats are needed. All chords and natural tones are available by the use of tabs 43, 74 and 80. By simultaneously depressing a plurality of selected finger tabs a great number of different chords may be obtained in addition to those chords which are available by depressing the individual finger tabs.

It will be apparent that the player may readily obtain the desired chords without confusion as to the strings to be stopped and as to the fret positions at which the strings must be engaged. The chords may be played without the need of great manual dexterity on the player's part and with positive string-engaging action. The possibility of accidentally striking a discordant string is completely eliminated.

The attachment may be clamped at different places on the neck of the guitar, thereby enabling the key to be changed without altering the mode of playing. The attachment provides a choice of two different keys at each setting.

While a specific embodiment of a chord playing attachment for guitars has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A chord playing attachment for stringed instruments comprising a housing, means for securing said housing on the neck of a stringed instrument in overlying relation to the strings, a plurality of levers pivotally secured to and extending into said housing, each lever being provided with an external actuating element projecting laterally of the housing, respective vertically movable members contained within the housing, means pivotally connecting said vertically movable members to the respective levers for pivotal adjustment around axes parallel to the respective pivotal axes of the levers, and a pair of spaced depending string-engaging elements carried by each vertically movable member, said pair of elements being spaced on opposite sides of the pivotal connection of the associated vertically movable member.

2. A chord playing attachment for stringed instruments comprising a housing, means for detachably securing said housing to the neck of a string instrument in overlying relation to the strings, a plurality of levers pivotally secured to and extending into the housing, each lever being provided with an external actuating element projecting laterally of the housing, respective ver-

5 tically movable members contained within the housing, certain of said members extending transversely of the housing and at least one of said members extending longitudinally of the housing, means pivotally connecting said members to the respective levers for free pivotal adjustment around axes parallel to the respective pivotal axes of the levers, spring means biasing the members upwardly, and a pair of spaced depending transverse string-engaging elements carried by each member, said pair of elements being spaced on opposite sides of the pivoted connection of the associated member.

10 3. A chord playing attachment for stringed instruments comprising a housing, means for securing said housing on the neck of a stringed instrument in overlying relation to the strings, a plurality of levers pivotally connected to a side portion of and extending transversely through said housing, respective vertically movable horizontal rectangular plate elements contained in the housing and underlying the respective levers, spring means biasing the vertically movable members upwardly, a pair of vertical plate elements pivotally secured at their intermediate portions to the respective opposite transverse edges of each vertically movable member for free pivotal adjustment in transverse planes, and a pair of depending string-engaging lugs carried by each plate element, said lugs being spaced on opposite sides of the pivotal connections of their associated plate elements.

15 4. A chord playing attachment for stringed instruments comprising a housing, means for securing said housing on the neck of a stringed instrument in overlying relation to the strings, a plurality of levers pivotally secured to the housing outwardly adjacent one side edge thereof and extending through said housing, respective vertically movable members contained in the housing, each vertically movable member being engageable by one of said levers, and depending string engaging elements movably secured to each of the vertically movable members.
